UNITED STATES PATENT OFFICE.

HENRY J. DAVIES, OF BROOKLYN, NEW YORK.

CLOCK-CASE.

SPECIFICATION forming part of Letters Patent No. 228,613, dated June 8, 1880.

Application filed April 29, 1880. (No model.)

To all whom it may concern:

Be it known that I, HENRY J. DAVIES, of the city of Brooklyn, in the county of Kings and State of New York, have invented certain new and useful Improvements in Clock-Cases, of which the following is a specification.

The object of my invention is to produce a highly-finished and light yet very strong clock-case of metal and glass; and to this end it consists in a novel construction of a case of several pieces of sheet or plate metal, which, by being separately stamped or pressed by dies, or otherwise formed by the cheap processes used in fashioning sheet metal, and separately plated or lacquered, enable the desired result to be produced.

One of the important features of the case consists in a top or entablature therefor, formed of a filling-piece covered with sheet metal and provided with recesses for the reception of nuts upon the ends of the upright bolts, by which the parts of the case are connected and secured together.

The invention also embraces certain improvements in the construction of the upright metallic portions of the case for the reception of the glass, and to provide for securing the said parts to the base and entablature, and in the mode of combining or connecting together the several parts of the case.

In the accompanying drawings, Figure 1 represents an irregular vertical section through a clock-case constructed according to my invention. Fig. 2 represents a horizontal section through the same. Fig. 3 represents a detail perspective view, illustrating the method of securing the tubular casings for the upright bolts to the base and entablature of the case.

Fig. 4 represents a perspective view of the lower end of one of said tubular casings. Fig. 5 represents a perspective view of a securing plate or device for holding the tubular casing rigidly in position. Fig. 6 represents a perspective view of a portion of the base. Fig. 7 represents a perspective view of a portion of the door of the case, and Fig. 8 represents a perspective view of the devices used for securing the glass sides of the case.

Similar letters of reference designate corresponding parts in all the figures.

A designates the hollow base of the case, which is represented as formed of sheet metal by stamping or pressing.

B designates the top or entablature of the case, composed of a filling, a, of wood, having its edges of the desired form of the molding of the entablature, and covered upon both sides with thin metal plates b b', which are lapped and bent one upon the other at the edge.

C designates bolts, which connect the base and entablature, and D designates tubes, which form casings for said bolts, and present the appearance of columns at the upright corners of the case. These tubes, which may be made with or without a longitudinal seam, are of a length to fit between the base and entablature and keep them at a proper distance apart upon the tightening of the nuts upon the bolts C. These bolts pass through the base, but do not pass entirely through the entablature, passing only through holes of a sufficient size to receive them in the bottom plate, b, of the latter, and screwing into nuts s, placed in shallow recesses e in the wood filling, such recesses being wider than the bolt-holes in the plate b, and of a form to prevent the turning of the nuts, which have their bearing on the interior of the plate b, within their respective recesses e, leaving the upper covering-plate, b', intact, and leaving solid wood over the said recesses to form a continuous unbroken support to the thin metal plate b'.

The tubular casings D are retained in their proper position against the entablature and base of the case by means of locking plates or devices E, which are shown clearly in Fig. 5, and which are applied to the upper and lower ends of the tubular casings. These locking plates or devices comprise a round washer-like portion, d, having a central hole for the passage of the bolt, and adapted to fit within the tubular casing D, a shank or tongue, e, which is adapted to fit in a notch, f, provided for it in the end of the tubular casing D, and prongs or lips g, which are inserted through holes h in the base and the bottom

plate, *b*, of the entablature, and may be bent over or clinched, if desired. By means of these locking plates or devices the tubular casings are held securely at each end and kept from 5 shifting relatively to the bolts.

The sides and back of this case may be composed of plates of glass or of other material, and the means for holding said plates consist of upright metal strips *F* *F'*, the central portions of 10 which are curved to conform to the exterior of the tubular casings *D*, and the marginal portions of which are bent or turned outward to form flanges *j* and *j'* at a right angle to each other. The curvature of the inner strips, *F*, is such 15 that their concave faces fit closely to the tubes *D*, and that of the outer strips, *F'*, is such that their concave faces fit closely to the convex faces of the strips *F*, the flanges *j* *j'* being respectively at such distance apart as to form 20 between them grooves *O*, for the reception of the glass, as shown clearly in Figs. 2, 3, and 8.

The strips *F* *F'* are each shown as notched at their lower ends, *k*, so as to receive the shank or tongue *e* of the locking-plate *E*, and 25 are thereby secured and stayed.

The tubular casings *D* are here represented as sunk or recessed in the corners, so that they are almost parallel with the sides of the case.

The door *H* of the case is here represented 30 as composed of a glass plate set in a rectangular frame, *l*, channeled to receive the glass, and having its upper side mortised to permit of the glass being inserted through the top of the frame.

35 The several parts of the case may be finished in any desirable manner, as by plating or otherwise, and by my invention I enable a very strong and light case to be produced, which shall present a fine appearance, and which at 40 the same time may be cheaply constructed.

The several metallic portions of the case are plated or otherwise finished before being put together.

The bolts *C*, being fixed in the entablature, 45 the tubular casings *D*, with their attached

strips *F* *F'*, are placed over them and the glass sides slipped downward into the grooves or channels *O*. The base *A* is then placed in position, and by screwing up the nuts upon the lower ends of the bolts *C* the several parts 50 of the case are secured rigidly together.

What I claim as my invention, and desire to secure by Letters Patent, is—

1. The combination, in a clock-case, with a base, columns for supporting an entablature, 55 and bolts and nuts for securing together the base, entablature, and columns, of an entablature composed of a filling, *a*, of wood, and covering-plates *b* *b'* of metal, the lower covering-plate, *b*, being perforated for the passage of 60 the bolts, and the filling *a* having recesses *c* provided for the nuts *s* at the upper ends of the bolts *C*, which have a bearing upon the said plate *b*, leaving the upper plate, *b'*, intact, substantially as specified. 95

2. The combination, in a clock-case, with a base and entablature, interposed tubular columns, and clamping-bolts passing through said columns, of locking-plates each comprising a circular portion fitting the interior of a tubular column, a shank entering and passing through a notch in said column, and prongs or spurs entering holes in the base and entablature, the said circular portions also having central holes for the passage of the clamping- 70 bolts, all substantially as specified. 75

3. The combination, in a clock-case, with a base, entablature, and interposed tubular columns, of curved flanged strips *F* *j* *F'* *j'*, secured to said columns, substantially as and for the 80 purpose specified.

4. The combination of the tubular columns *D*, the locking-plates *E*, and the curved strips *F* *j* *F'* *j'*, secured to the said columns and notched at the ends to engage with said locking-plates, substantially as specified. 85

HENRY J. DAVIES.
